UNITED STATES PATENT OFFICE.

FRANCIS M. SISK, OF ATLANTA, GEORGIA, ASSIGNOR, BY DIRECT AND MESNE ASSIGNMENTS,
TO J. L. DE GIVE, OF ATLANTA, GEORGIA.

GIN-SAW-FILING MACHINE.

No. 884,770.

Specification of Letters Patent.

Patented April 14, 1908.

Application filed January 6, 1906. Serial No. 294,940.

To all whom it may concern:

Be it known that I, FRANCIS M. SISK, a citizen of the United States, residing at Atlanta, in the county of Fulton and State of Georgia, have invented new and useful Improvements in Gin-Saw-Filing Machines, of which the following is a specification.

My invention relates to improvements in that class of saw filing machines, in which vertically reciprocatory and circular files sharpen the saw without removal from the mandrel, and the object of my invention is to provide a machine having reciprocatory file rods and to reciprocate the same on the teeth 15 of the saw in a regular series of reciprocatory rotary motions; to adjust the saw-carrying frame with reference to the saw; to provide means whereby the circular file may cut in the correct position between the teeth, and 20 to throw all the files into inoperative position during the feed of the saw.

Other objects will become evident in the description of the construction and operation of the device.

I attain these objects by the mechanism illustrated in the accompanying drawings, in which:

Figure 1 is a side elevation of the complete machine; Fig. 2 is a detail of the frame-work, 30 showing the construction of the supporting frame; Fig. 3 is a front view of Fig. 2; Fig. 4 is a rear view of a part of the leg; Fig. 5 is a cross section of the leg taken at $\bar{V}^1$; Fig. 6 is a section of the main operating cam; Fig. 7 is a 35 rear view of the same; Fig. 8 is a detail partly in section of the feeding device and connected parts; Fig. 9 is a detail plan view of the reciprocating file operating mechanism; Fig. 10 is a detail showing the manner of connecting the rock lever with the reciprocating files; Fig. 11 is a plan of the circular file bracket 40 and related parts; Fig. 12 is a vertical section of the same; Fig. 13 is a detail side view of the reciprocating files and their operating mechanism; Fig. 14 is a front detail view of the same, in connection with the saws; Fig. 15 is a cross section of the file and file rods and collar, showing the method of securing the file to the file rod; Fig. 16 is a detail of the 45 saw clamp, shown in three positions; Fig. 17 is a front elevation of the supporting forks for maintaining the machine in position upon the saw cylinder; and Fig. 18 is a plan of a part of the ratchet plate. Fig. 19 is a front 50 detail view of the machine.

Like numerals of reference designate like parts in the drawings:

The letter A designates a wooden bar which is provided with a groove on its under face into which extends a tongue on the foot-piece V and a tongue on an extension from the frame B. The bar is provided with a series of holes, as shown in Fig. 4, and bolts B' and V', provided with nuts, pass through the holes in the extension and foot piece to secure the parts together, thus providing means for adjusting the length of the supporting bar.

In the frame B (Fig. 8) is journaled a short shaft B² having secured to the outer end 70 thereof by means of a set screw C³ a cam C, provided on its inner face with a cam groove C', comprising, as clearly shown in Fig. 7, three symmetrical sections for a purpose to be hereinafter set forth. Upon the shaft B² 75 is also secured a pinion D and two cams, D' and D². In the embodiment herein shown and described the cams D', D² and C and the pinion D, are integral, and a crank arm C² is provided for rotating the shaft.

In the upper part of the frame B is a stud shaft G', having pivoted thereto a rock-lever G. The rock-lever G is provided with a stud at one side of the center, as shown in Fig. 14, which carries a friction roller G³ running in the cam groove C'. Each of the outer ends of the rock-lever G is provided with a socket in which plays the ball head of a screw g', the said screw being screwed into a threaded opening in a collar H³ secured by a set screw 85 to a file rod H thus giving a ball and socket connection between the rock-lever and the file rod. Pivoted to the frame B by screws O', below and upon each side of the stud shaft G', are two bearing blocks o, each block provided with an upper bearing O and a lower bearing O² for the file rod H, above and below the attachment to the rock-lever G. The lower end of the file rod H is deeply grooved (see Fig. 15) for the reception of the 90 triangular file H', and surrounding said file is a collar H², provided with a set screw bearing upon the outer part of the file. In the face of each of the bearing blocks o is a series of holes O⁴ in which are adapted to screw the 95 ends of a torsional spring O⁴⁰. The bearing blocks are normally inclined so that the files cross each other at an angle of about 30 degrees and by varying the position of the 100 spring O⁴⁰ a varying degree of pressure by the 105

110

files upon the saw may be secured. On their inner edges the bearing blocks o are provided with set screws O^3 for a purpose to be herein-after described.

5 Journaled in a rearward extension of the frame B is a rock shaft I' supporting the bell crank lever I, one arm of which extends through a suitable opening in the frame B (Fig. 8) into the path of the cam D', while 10 the other arm is pivotally attached to a pawl arm J. The arm J has attached thereto by a pin and slot connection a wide pawl J' adapted to engage the teeth of the saw being operated upon. Pivoted to the extreme rear 15 end of the pawl arm J is a rod J² which passes loosely through a hole in the extension of the frame B, and is provided with a nut K to secure it therein. A coiled spring J^X surrounds the rod J² and tends to press the rod 20 away from the frame B, thus keeping the pawl in contact with the saw teeth (Fig. 1).

Secured to the rearward extension of the frame B by a bolt T, is a slotted fork L having secured to one side thereof and parallel 25 therewith a second fork L', said forks being adapted to support the frame B by resting upon the spacing block U between the saws. For regulating said frame B with relation to the forks L and L', and consequently 30 positioning the files to the saw teeth, the supporting member L is provided with a projection or shoulder M^X adapted to bear against an adjusting pin M which is screw-threaded through an integral eye m on the frame B. 35 Thus by loosening the nut of the bolt T and setting the pin M the files may be set at various positions.

Below and to one side of the shaft B² is a bracket R (Fig. 1) provided with an arm R^X, 40 pivoted by means of a screw R' to a bracket B⁶ extending forwardly from the frame B. The arm R^X is extended beyond the pivot R' and its outer end is provided with a set screw R³ adapted to be engaged by the cam D².

45 Journaled in bearings at either end and at the center of the bracket R, is a shaft F' (Fig. 12) having secured thereto at the outer end a pinion E adapted to be engaged by the pinion D, and having formed upon its inner 50 end a left-handed screw. Midway of the shaft F' is secured a collar R⁴ between which collar and the bearing upon each side is a coil spring encircling the shaft for a purpose to be hereinafter described. Through the 55 threaded inner end of the shaft F' is a pin E⁴ projecting approximately one-eighth of an inch at either side of the same. Over the threaded inner end of the pin is slipped the circular file F, it being provided with key- 60 ways for the reception of the pin ends, and a nut F² screwed upon the threaded end holds the file securely in place. A spring R⁷ is seated with its lower end in a hole in the bracket R and its upper end in one of a series 65 of holes in the frame B. By placing the up-

per end in different holes of the series, a varying pressure may be obtained, as desired.

On the lower part of the inner bracket is an extension R⁶ adapted to act as a stop when the circular file is lowered by abutting against 70 the part N, described later on.

Owing to the above described arrangement of the collar R⁴ and the coil springs R⁵, longitudinal movement of the shaft F' is permitted to a limited extent, thus providing 75 for the proper seating of the circular file, between the saw teeth.

Attached to the frame B below the bracket R by screws or otherwise is a clamp (Figs. 1 and 16) consisting of two jaws N and B⁷ 80 which are secured together by two screws N', and have between them a spacing rib N² that runs crosswise thereof. The ends of these jaws are recessed and turned to provide noses, the nose of B⁷ slightly offsetting and 85 overlapping the nose of jaw N, and when in applied position on the frame said turned ends project upwardly and a trifle in advance of the circular file F. In this position their function is to receive the periphery of 90 the saw-blade between their co-acting faces for steadyng and to deflect the same whereby the saw teeth may be set to the proper angle for sharpening. Said deflection being effected by the end of the jaw B⁷ offsetting 95 the end of jaw N. By loosening one of the screws N' and tightening the other, this inclination of the saw periphery may be varied.

During the feeding of the saw it is necessary that the files be removed from the saw 100 teeth since the saw commences to turn at that time. I provide for this by the construction illustrated in Figs. 8 and 14. P, is a reciprocating bar having a triangular or cone-shaped head. The bar P moves in 105 guides on the frame B and rests with its lower end on the arm I² of the bell crank lever I, and the cone-shaped head of the bar bears against the set screw O³ of the bearing blocks o so that when the said bar is elevated 110 by the arm I² the cone-shaped head moves the upper ends of the bearing blocks outward and swings the files away from the saw. The bar descends by its own weight.

Having now set forth the structure of my 115 invention, I will proceed to describe its operation as a whole. The device having been placed with the forks L, L', resting on the space blocks between the saws and with the foot V on the floor, the leg V being adjusted 120 to such length as desired, the device is leveled by the nut T and set screw M. Power being applied to the crank, the cams C, D', D² and the pinion D are set in motion. The cam C' acting on the roller G³ actuates the 125 rock-lever G, which, by means of the ball and socket connection, reciprocates and at the same time partially rotates the file rods H. On account of the peculiar conformation of the cam C' three complete reciprocations 13

take place during each revolution of the cam. The pinion D rotates the pinion E and consequently the circular file F. These gears are in the ratio of 52 to 17, that is, 52 teeth on the pinion D and 17 on the pinion E. On account of this one revolution of the pinion D causes 3-1/17th of a revolution of the pinion E. In other words, the circular file makes three revolutions and a fraction of 10 a 4th; thus always starting each series of revolutions at a different point on the periphery. At the completion of the above movements, the cam D² strikes the set screw R³ and elevates the circular file from the saw teeth, the cam D' strikes the rocker arm L² which moves the pawl arm and pawl, thus feeding the saw one tooth. Before the feed takes place, however, the arm I² elevates the bar P, which acts on the set screw O³ to 20 swing the files away from the saw teeth.

It will be noticed from an inspection of the drawings, that the clamping jaws N and B⁷, are provided with alined recesses in their upper edges directly below the circular file, 25 and that their ends are upturned. This construction permits the jaws to engage the periphery of the saw in front of and behind the circular file whereby to steady the saw on both sides of the circular file.

30 Having thus described the construction and operation of my device, what I claim and desire to secure by Letters Patent is:—

1. In a saw filing machine, the combination with the frame, a saw feed of bearing blocks pivotally mounted on said frame, file rods mounted for reciprocation and rotation upon said bearing blocks, a rock lever pivoted between the file rods, means for automatically spreading the file rods during the 35 inoperative movement of said file rods, means for regulating said movements of the bearing blocks, and a universal joint connection between the file rods and the adjacent ends of the rock lever, whereby the rocking of the lever will reciprocate and partially rotate the file rods.

2. In a saw filing machine of the class described, the combination with the frame provided with an extension on the front thereof, 40 of forks connected with the rear of the frame

and adapted to rest upon the space blocks of the saws, a leg comprising a foot piece and grooved bar, said foot piece and the extension of the frame being provided with tongues engaging the groove of the bar whereby to 55 adjust the length of the leg, means for securing the parts in their adjusted position, and filing mechanism in connection with the frame.

3. In a saw filing machine, the combination with the frame, of a sharpening means in the frame, a clamp comprising a plurality of plates connected with the frame directly below said sharpening means and adapted to engage opposite sides of the saw, one of 60 said plates offsetting its adjacent plate for receiving and deflecting the periphery of the saw in front of and behind the file whereby said saw may be held for said sharpening means.

4. In a saw filing machine, the combination with the frame, of a sharpening means in the frame, plates connected with the frame and engaging opposite sides of the saw, said plates having uneven clamping faces whereby to engage and deflect the periphery of the 70 saw in advance of the file.

5. In a saw filing machine, the combination with the frame, of saw sharpening means in connection therewith, and a clamp comprising jaws for engaging the opposite sides of the saw, the engaging face of one of said jaws being concave and the other convex whereby to tension the periphery of the saw.

6. In a saw filing machine, the combination with the frame, of a circular file mounted for rotation thereon, means for rotating the file, and means in connection therewith for moving said file into inactive position at the end of a predetermined series of complete 85 revolutions or fraction of a revolution, whereby to prevent unequal wear of the file.

In testimony whereof I have hereunto set my hand in presence of two subscribing witnesses.

FRANCIS M. SISK.
